Conrad Harris & Paul M. Goines of Cincinnati, O.
Letters Patent No. 748 - Dated Dec. 11, 1853:

The Schedule referred to in these Letters Patent and making part of the same.

To all whom it may concern,

Be it known, that we Conrad Harris & Paul M. Goines, both of Cincinnati, Hamilton County, State of Ohio, have invented or produced a new and original design for a six plate or box stoves, and we do hereby declare the following to be a full and exact description of the same, reference being had to the annexed drawings and to the letters of reference marked thereon, to wit: letter A, being a perspective view of the stove.

That we claim thereon as new and desire to secure by letters patent is the moldings, flutes and scrolls, arranged as set forth in the annexed drawings to form an ornamental design for six plate or box stoves.
